UNITED STATES PATENT OFFICE.

JOHN F. SHOOTER, OF GARY, INDIANA.

SPIRIT LEVEL.

Application filed February 24, 1926. Serial No. 90,293.

This invention relates to spirit-levels especially adapted for use by carpenters and other mechanics.

Briefly stated, an important object of this invention is to provide a spirit-level in which the bubble tube is yieldably supported so that the same is rendered capable of withstanding shocks to which the same is invariably subjected.

10 A further and equally important object of the invention is to provide a spirit-level having simple means whereby the bubble tube may be adjusted when necessary.

15 A further object is to provide a spirit-level of the character specified which is of highly simplified construction, durable in use and cheap to manufacture.

20 Other objects and advantages will be apparent during the course of the following description.

In the accompanying drawing forming a part of this application and in which like numerals are employed to designate like parts throughout the same,

25 Figure 1 is a fragmentary side elevation of the improved spirit-level, parts being shown in section.

Figure 2 is a vertical transverse sectional view taken on line 2—2 of Figure 1.

30 Figure 3 is a fragmentary side elevation of the improved level, parts being shown in section.

Figure 4 is a fragmentary edge elevation illustrating the adjustable attaching means for one of the bubble tubes.

35 In the drawing wherein for the purpose of illustration is shown a preferred embodiment of the invention the numeral 5 designates a stock having a recess 6 intermediate the ends thereof to receive a bubble tube 7.

Figure 1 plainly illustrates that the bubble tube has its ends rounded and received in compressible cups 8 of rubber or the like, which cups are in turn received in the sockets 45 of attaching members 9.

In carrying out the invention the socket members 9 which snugly receive the cups 8 are provided with attaching ears 11 secured to the bottom wall of the recess 6 by screws 50 12 or other fastening devices. Particular attention is directed to the fact that cushions 14 of compressible material are confined between the ears 11 and the bottom wall of the stock 5 and provide a means whereby one 55 or both of the ends of the bubble tube 7 may

be raised or lowered as the occasion requires. In other words, by tightening one or both of the screws 12 the cushion or cushions as the case may be are compressed. This provides a means whereby the level and 60 more specifically the bubble tube of the same may be adjusted.

Figure 2 illustrates that a cover plate 16 is secured by screws or other fastening devices at its ends to the stock 5 and extends 65 over the bubble tube to protect the same. Figure 2 clearly illustrates that the plate 16 is confined between the side walls of the recess 6 and is provided with spaced openings 20 for affording a view of the bubble tube 70 7. It will be seen by reference to Figure 2 that the central portion of the protecting plate 16 is unbroken and extends over the crown of the bubble tube to effectively protect the same. In other words, nails or the 75 like cannot drop on the crown of the bubble tube and any objects which drop onto the sides of the bubble tube will strike only glancing blows and would not ordinarily break the tube. However, the central closed 80 portion of the plate 16 does not prevent the operator from clearly observing the position of the bubble in the tube 7.

With reference to Figures 3 and 4 it will be seen that a second bubble tube 30 is arranged in a transverse opening 31 and is adapted for use in connection with vertical or substantially vertical work. Figure 3 clearly shows that the bubble tube 30 has its ends positioned in cups 33 of rubber or other 85 yieldable material and the cups 33 are in turn snugly received in the end portions of an attaching and protecting tube 34, the upper side of which is formed with an opening 90 36 to afford a view of the bubble tube. 95

In carrying out the invention the attaching and protecting tube 34 receives the boss 39 on an attaching plate 40, the attaching plate being secured to the stock by screws or other suitable fastening devices.

100 The opposite end of the attaching and protecting tube 34 is threaded into a boss 44 of a second attaching plate 46. Figure 4 plainly illustrates that the end portions of the attaching plate 46 are extended beyond the boss 44 and are provided with series of openings 48 to selectively receive screws 49 whereby the attaching plate 46 and consequently the bubble tube 30 may be adjusted. The provision of the multiplicity of holes 105 110

48 makes it a simple matter to change the position of the screws 49 when it is desired to raise or lower one end of the bubble tube 30. Of course the frequency with which the 5 bubble tube 30 must be adjusted depends largely on the care the level receives in use and the work it is called upon to do. Figure 4 clearly illustrates that one edge of the stock is provided with a shallow recess some- 10 what greater in area than the area of the attaching plate 46 so that the attaching plate may be adjusted within reasonable limits.

With reference to the foregoing description taken in connection with the accompanying drawing it will be seen that a level constructed in accordance with this invention is capable of use in connection with vertical and horizontal work and may be ad- 15 justed from time to time as the occasion re- quires and the yieldable supporting means for the bubble tubes reduce the possibility of breakage of the tubes to a minimum so that if the level is handled roughly the tubes 20 will remain unbroken. Also, threading the tube 34 firmly into the boss 44 will prevent it from turning to obstruct the bubble 25 tube 30.

Having thus described the invention what is claimed is:

A level comprising the combination with a stock having an opening extending entirely therethrough and a bore extending entirely therethrough at a right angle to said opening and communicating with a portion thereof, of a closure plate for one end of said bore and secured to said stock, said plate having a boss extending into said bore, a bubble tube disposed longitudinally in the bore and having a sliding engagement at one end over said boss whereby to dispose a portion of said tube within said opening, an end plate closing the opposite end of said bore and having an internally threaded boss extending into said bore in threaded engagement with the adjacent end of said bubble tube, stock attaching flanges at opposite ends of said plate, each of said flanges being formed with a plurality of closely associated apertures for the selective 40 reception of fastening elements whereby said plate may be adjusted in the stock to effect a movement of said bubble tube trans- 45 versely in the bore.

In testimony whereof I affix my signature.

JOHN F. SHOOTER.
